US00D738500S

(12) **United States Design Patent**
Richard et al.

(10) **Patent No.:** **US D738,500 S**
(45) **Date of Patent:** ** *Sep. 8, 2015

(54) **SEAL ANCHOR FOR USE IN SURGICAL PROCEDURES**

(71) Applicant: **Covidien LP**, Mansfield, MA (US)

(72) Inventors: **Paul D. Richard**, Shelton, CT (US);
Russell Heinrich, Madison, CT (US)

(73) Assignee: **Covidien LP**, Mansfield, MA (US)

(*) Notice: This patent is subject to a terminal disclaimer.

(**) Term: **14 Years**

(21) Appl. No.: **29/493,029**

(22) Filed: **Jun. 5, 2014**

Related U.S. Application Data

(63) Continuation of application No. 13/400,143, filed on Feb. 20, 2012, which is a continuation of application No. 12/244,024, filed on Oct. 2, 2008, now abandoned.

Primary Examiner — Wan Laymon

(57) **CLAIM**

The ornamental design for the seal anchor for use in surgical procedures, as shown and described.

DESCRIPTION

FIG. 1 is a top perspective view thereof;

FIG. 2 is a top plan view thereof;

FIG. 3 is a side elevational view thereof;

FIG. 4 is a front elevational view thereof; and

FIG. 5 is a side elevational view thereof;

FIG. 6 is a rear elevational view thereof; and,

FIG. 7 is a bottom plan view thereof.

The broken lines shown in the figures represent portions of the seal anchor and the tubing for use in surgical procedures that form no part of the claimed design.

1 Claim, 4 Drawing Sheets
